UNITED STATES PATENT OFFICE.

JOHN R. GAMMETER, OF AKRON, OHIO, ASSIGNOR TO THE B. F. GOODRICH COMPANY,
OF NEW YORK, N. Y., A CORPORATION OF NEW YORK.

BALLOON AND PARACHUTE.

1,359,689.

Specification of Letters Patent. Patented Nov. 23, 1920.

Application filed July 11, 1918. Serial No. 244,498.

To all whom it may concern:

Be it known that I, JOHN R. GAMMETER, a citizen of the United States, residing at Akron, in the county of Summit and State 5 of Ohio, have invented a certain new and useful Balloon and Parachute, of which the following is a specification.

This invention relates to means for effecting an emergency descent from a balloon 10 or other air-craft by the aid of a parachute or any equivalent slow-falling flotation device, and its principal objects are, first, to save time in the launching of the parachute and its load and, secondly, to enable the 15 aeronaut to save the instruments, records and other movable equipment ordinarily carried in the car or basket.

I accomplish these objects by employing a parachute, and a car or basket suitably attached thereto, as by a normally slack connection, said car being suspended from the body of the air-craft by a detachable connection normally bearing the weight of the car and its load and controllable at will 25 from the car, so that the entire car with its contents may be launched by merely operating said detachable connection.

Further objects are to provide improved 30 means for storing the parachute in folded condition when not in use, and to furnish an improved catch mechanism or "snap-off" adapted securely to hold the basket suspended from the rigging at a plurality of points and capable of being instantly detached 35 simultaneously at said points when a descent is made.

Of the accompanying drawings,

Figure 1 is a side elevation of the lower 40 part of a balloon with the parachute holder suspended therefrom and the parachute launched and opened out.

Fig. 2 is a side elevation on a larger scale, partly broken away, showing the holder, the parachute and the basket.

Fig. 3 is a detail elevation of the catch- 45 mechanism and adjacent parts.

Fig. 4 is a section on the line 4—4 of Fig. 3.

Fig. 5 is a reverse plan view of the 50 container, partly broken away.

Fig. 6 is a section on the line 6—6 of Fig. 5.

In the drawings, 10 is a balloon from which the parachute holder 11, 12 is suspended by means of the rigging ropes 13,

14. The holder consists of the usual wooden concentrating ring 11, forming a part of the rigging and connected with the ropes 13, which latter are shown spread out in Fig. 1, but gathered to an apex in Fig. 2, and a 60 frusto-conical inverted can or container 12 for storing the umbrella 15 and cords 16 of the parachute in a folded condition, together with the wooden ring 17 to which the lower ends of said cords are attached, this 65 container being suspended by the ropes 14. The container is closed at the top by a permanent end-closure 18, to which the upper end of the parachute is tied by a breakable cord 41, and I provide it with a bottom 70 cover 19, consisting of a cloth body in whose rim is bound an elastic rubber ring 20 overlying a rigid ring 21 in the lower edge of the container 12, the elastic ring being adapted to stretch and pass downwardly 75 over the rigid ring when the parachute is released. A pair of crossed bands 19^a having their ends wrapped around the edge of and attached to the cover 19 are provided for rolling the latter down over the fixed 80 ring 21 when tension is placed upon said bands.

22 is the aeronaut's basket suspended by ropes 23 from the extremities of a cross-bar 24 which is connected with the parachute 85 ring 17 by four ropes 25 passing through eyelets 26 in the cover and the bands 19^a. The ropes 25 are slack when the parachute is in its container. The connections of the ropes 23 and 25 to the bar 24 may in practice 90 advantageously be located closer together than shown, to provide a more direct pull from the basket to the parachute ring 17.

At diametrically opposite points on the 95 under side of the ring 11 two short cylindrical bars 27, preferably made hollow for lightness as shown in Fig. 4, are secured by lashings 28. These bars are the keepers for a pair of catch or "snap-off" levers 29 fulcrumed at 30 on the bar 24. Each catch-lever includes a lower cross-bar or stud 31, an upper cross-bar 32, and a pair of side plates 33 straddling the bar 24, there being a U-shaped metal wear-plate 34 interposed 100 between said bar and the catch-lever. Each lever has a hooked short arm 35 at its upper end partially overlying the bar 27. 36 is a horizontal tie-rod pivoted by one end on the stud 31 at the lower end of the left-hand 110

catch-lever 29 as viewed in Fig. 2, and having a hook 37 at its other end adapted to engage from beneath with the stud 31 at the lower end of the right-hand catch-lever, 5 when the said levers have their hooks 35 in engagement with the bars 27. The hooked end of the tie-rod is suspended in its catching position as shown in Fig. 4 by means of a breakable cord 38, and is provided with a 10 releasing cord 39 for pulling it downward to break the cord 38. A normally slack cord 40 suspends said hooked end after the cord 38 is broken.

In the operation of my invention, the umbrella 15, cords 16 and ring 17 of the parachute are normally stowed in folded condition within the container 12 as shown in Figs. 2, 5, and 6, and the upper end of the parachute is tied to the end closure 18 by 15 the breakable lashing 41. The elastic ring 20 of the cover 19, overlying the rigid ring 21 on the container, maintains said cover in place, and the parachute is thoroughly protected from the weather. The container being directly over the basket, the latter, when released, exerts a direct downward pull upon the parachute. The catch-levers 29 being engaged with the keeper bars 27 on the holder ring 11, as indicated in Figs. 2, 3, 20 and 4, the basket will be securely suspended from said ring. To drop the basket and release the parachute, the aeronaut pulls downwardly on the releasing cord 39 so as to break the cord 38 and disengage the hook 35 from the right-hand catch-lever. This allows the hooked upper ends 35 of said catch-levers simultaneously to become disengaged from the keeper bars 27, and the basket drops away from the ring 11 by 25 gravity. The cross-bar 24, drawing on the parachute ring 17 through the ropes 25, pulls the cover 19 away from the container 12, and draws the parachute out of said container, its upper end remaining connected with the 30 end closure 18 until it breaks the lashing 41. The released parachute descends and opens in the usual manner. In consequence of the basket being detachable from the balloon and adapted to be suspended by the parachute, the launching is instantly effected with the minimum of effort and danger, and the occupants and all instruments and records or other equipment which the basket 35 may contain can be safely landed.

55 I claim:

1. The combination, with the body of an air-craft, of a parachute, a car adapted normally to contain the aeronaut and his equipment and connected with said parachute, 60 means normally suspending the weight of the car and its load from the air-craft body, said means including a detachable connection, the operation of which causes the car to be launched, and means connecting the top 65 of the parachute with the air-craft prior to

and during the initial movement of the car away from the air-craft.

2. The combination of a balloon comprising a gas envelop and a car-suspending ring supported thereby, a car or basket, means 70 normally suspending the weight of said car and its contents from said ring and including a detachable connection controllable from the car, and a parachute detachably connected with the gas envelop and attached 75 to the car by a normally slack connection extending through the opening in said ring.

3. The combination of a balloon comprising a gas envelop and a support suspended therefrom, a basket, snap-off devices connecting said basket with the support at a plurality of points on the latter, a parachute detachably connected with the balloon for supporting the basket when released, and means for actuating said snap-off devices simultaneously at the several supporting points. 80

4. The combination of a balloon comprising a gas envelop and a ring suspended therefrom, a basket, a pair of snap-off hooks 90 suspending the basket from opposite points on the ring and connected for simultaneous release, and a parachute detachably supported on the balloon above said ring and connected with the basket through the opening in the ring. 95

5. The combination of a balloon comprising a gas envelop and a basket-support suspended therefrom, said support having a pair of hook-engaging members, a hook support, a pair of hooks pivoted on said support and detachably engaging said members, a rod pivoted to one of said hooks and having hooked connection with the other for holding the hooks in engagement with said members, a basket suspended from said hook-support, and a parachute connected with said basket. 100

6. The combination of a balloon comprising a gas envelop and a ring suspended therefrom, a parachute-container mounted above said ring in line with the opening thereof, a basket detachably suspended from said ring, and a parachute stowed in said container and connected with the basket 110 through said ring opening. 115

7. In a parachute holder, the combination of an inverted container having a rigid lower rim, a bottom cover comprising an elastic ring overlying said rigid rim, a web 120 whose margin ensheathes said ring, ring-rolling bands crossing the bottom face of said web and having their ends wrapped around the margin of the latter, and a parachute folded in said container and having a suspender extending through said cover. 125

8. The combination, with the body of an air-craft, of a normally collapsed parachute supported thereby, a car adapted to contain the aeronaut and his equipment, a normally 130

slack connection between the car and para-chute, and means normally suspending the weight of the car and its load from the air-craft body, said means including a detachable connection, the operation of which causes the car to be launched, the downward movement of the freed car taking up

the slack in the connection with the para-chute and pulling the latter away from the air-craft body.

10

In testimony whereof I have hereunto set my hand this third day of July 1918.

JOHN R. GAMMETER.
